SPOON OR SIMILAR ARTICLE

Albert Edward Allen, Utica, N. Y.

Application March 15, 1954, Serial No. 29,500

Term of patent 14 years

(Cl. D54—12)

Fig. 1

Fig. 2

Fig. 1 is a front view of a spoon or similar article showing my new design.

Fig. 2 is a sectional view of the spoon shown in Fig. 1 taken along lines 2—2 of Fig. 1.

The design shown on the spoon of this invention may also be applied to other articles of tableware such as knives and forks.

I claim:

The ornamental design for a spoon or similar article, as shown and described.
